UNITED STATES PATENT OFFICE.

JOHN F. MAKOWSKI, OF SAN FRANCISCO, CALIFORNIA, ASSIGNOR OF ONE-HALF TO
JAMES A. LEVENSALER, OF SAN FRANCISCO, CALIFORNIA.

WALL-BOARD AND PROCESS OF MANUFACTURING THE SAME.

1,349,778.

Specification of Letters Patent. Patented Aug. 17, 1920.

Application filed September 7, 1917, Serial No. 190,131. Renewed December 29, 1919. Serial No. 348,044.

To all whom it may concern:

Be it known that I, JOHN F. MAKOWSKI, a citizen of the United States, and a resident of the city and county of San Francisco, State of California, have made a new and useful Improvement in Wall-Boards and Processes of Manufacturing the Same; and I do hereby declare the following to be a full, clear, concise, and exact description of the same.

The invention relates to a new and useful art particularly to means for perforating stable or dry wall board; and to the process of forming holes or recesses therein adapted to act as key holes for bonding finishing plaster coats applied to the wall board, and to a new article of manufacture.

Among the objects of this invention are to provide means for economically and effectively processing a wall board of the nature described, to produce a new article of manufacture with improved qualities and at greatly reduced cost of production; to produce a wall board to which the finishing plaster can be applied and securely keyed with the minimum amount of plaster and waste, and to produce a wall board fire and water proof on the side opposite to that to which the plaster is applied. Other objects and advantages will appear as the description progresses.

In this specification and the annexed drawings, the invention is illustrated in the form considered to be the best, but it is to be understood that the invention is not limited to such form because it may be embodied in other forms, and it is also to be understood that in and by the claims following the description, it is desired to cover the invention in whatever form it may be embodied.

In the accompanying four sheets of drawings:

Figure 1 is a side elevation of an automatic perforating machine constructed in accordance with this invention.

Fig. 2 is a front view of the same.

Fig. 3 is a side elevation detail in cross-section of the perforating mechanism on the line III—III of Fig. 2.

Fig. 4 is a fragmentary enlarged detail of one side of the machine illustrating the punch operating mechanism in cross-section on the line IV—IV, Fig. 1.

Fig. 5 is a plan view from above of the same taken on the line V—V, Fig. 1.

Fig. 6 is a front elevation of the punching mechanism in cross-section on the line VI—VI, Fig. 3.

Fig. 7 is a plan view from above of the perforating machine taken from Fig. 1.

Fig. 8 is an enlarged fragmentary detail of the counter-sinking punch and die for forming the perforations in the wall board, Sheet 1.

Fig. 9 is a plan view of a fragmentary section of plaster board constructed and perforated in accordance with this invention.

Fig. 10 is a fragmentary detail view in cross section on the line X—X, Fig. 9, showing the laminated structure of the wall board.

Fig. 11 is a fragmentary detail diagrammatically illustrating the integral key formed on the coating of plaster when applied to the wall board as it would remain were the wall board removed.

Fig. 12 is a fragmentary detail in cross section of a hollow punch.

Fig. 13 is detail similar to Fig. 10, illustrating the form of recess formed by the hollow punch.

Broadly stated, the process of producing plaster wall board consists in flowing the plastic core composed of gypsum or other compositions in the unstable state, between two reinforcing sheets of prepared pulp paper, then rolling or pressing it into flat sheets, resulting in a core X of plaster faced on both sides by the sheets of paper X'—X², the whole forming a sheet of uniform thickness throughout, that is trimmed to size and permitted to set or season before being marketed. Other forms consist of slabs of plastic composition reinforced with fibrous and other matter. Because of the unstable condition to this product in the process of its manufacture, it has been found impracticable to form holes in it because the unstable plastic core would exude and destroy the marketability or practicability of the product.

I am aware, however, that wall boards of different composition have been formed with perforations or holes throughout, such holes being uniform in cross-section and having parallel sides.

In the process of forming plaster wall

boards in accordance with this invention, the dry or stabilized board is passed through a machine wherein it is punched, the punched portion being removed entirely from the board, as will be hereinafter more fully described.

In detail the construction illustrated in the drawings consists of an automatic punching machine, adaptable to processing wall board in accordance with this invention, having a bed 1 supported upon a suitable base 2, to which the upright sides 3—3 are bolted on opposite sides of the bed. The reciprocating breast beam 4 engages these guides 3 and is guided thereby in its vertical reciprocations. The cam shaft 5 is suitably journaled in bearings supported by the guides 3—3 and provided with the eccentrics 6 (see Fig. 4) engaged by the adjustable connecting rod 7 pivoted at 8 in the breast beam 4, whereby the rotation of the camshaft 5 causes the vertical reciprocation of the breast beam 4. The cam shaft is back-gearred through the gear 9 enmeshed with the driving pinion 10, fixed on the drive shaft 11, which is provided with a pulley 12 driven by the belt 13 engaging a pulley on the motor 14, the proper gearing being interposed between the motor and the cam shaft to give the necessary power and speed reduction. The breast beam 4 is provided with a series of alined male punches 15, fixed therein and coöperating with the female dies 16, to perforate the plaster board 17 set therebetween. To reduce the applied power necessary to perforate the board, and to prevent possible transverse cracking thereof in the punching process, it is advisable to arrange the male punches so that they perforate the board *seriatim*; this is easily accomplished by progressively lengthening the punches from the center to the edge as is illustrated in Fig. 6 or vice versa, the length being varied from the cutting edge to the tapered shoulder at 18, so that these shoulders will all strike the board simultaneously. It is important that these shoulders all strike the board simultaneously to bevel the edges of the holes by compression, whereby the resultant holes are of greater diameter at one surface of the board than at the opposite side, for reasons that will hereinafter be described. Two rows of punches can be provided as illustrated in Fig. 3, arranged in off-set relation out of longitudinal alinement and placed a uniform distance apart, the board being fed forward the space of two rows of holes at each operation.

60 The intermittent feeding mechanism comprises the two traction rollers 19 and 20 between which the plaster board 17 is fed. These traction rollers are fixed upon their respective shafts 21—22 and are rotated in

unison by the gears 23—24. The shaft 21 is rotated by a ratchet 25 fixed thereon engaged by the pawl 26, pivoted on the arm 27 formed on the hub 28 rotatable on the shaft 21. The hub 28 is operated by the cable 29 wrapped therearound and having its opposite ends fixed to the lever 30 and the frame of the machine at 31 respectively. The lever is pivoted at 32 and rests upon the cam 33 fixed on the shaft 5. The cam 33 is so timed that the rise of the punches out of the board, 75 brings the cam under the lever 30 which is raised thereby, which exerts a pull on the cable 29 to rotate the hub 28 which carries the ratchet 25 forward to rotate the traction wheels 19 and 20, pushing the board forward 80 a distance equal to the distance between the transverse rows of holes. This distance may be accurately regulated by varying the position on the lever 30 at which the cable 29 is attached.

When the cam 33 has passed underneath the lever 30 the tension of the spring 34 returns the arm 27 to the operative position for the next operation, the ratchet 26 returning without engaging the ratchet. 85

The board 17 laid on the receiving table 35 is supported on the rollers 36 from which it is conveniently fed between the feed rollers 19 and 20 beneath the punching machine and ejected onto the delivery table 37. 90

In producing the type of board illustrated in Fig. 9 having the backing sheet 38 placed thereon, means are provided in connection with the punching machine to apply this sheet as the board passes through 100 the machine. It is best accomplished by providing the sheet 38 in rolls as at 39, Figs. 1 and 2, mounted upon a cross shaft 40 suitably journaled in a superstructure on the machine. The sheet 38 is fed behind 105 the roller 41, over the top of the roller 42 and carried down to contact with the top face of the board. The roller 42 is journaled in the trough 43 containing paste submerging the lower portion of the roller 42, by which means a coating of paste is transferred to the surface of the paper 38 tractively passing over the roller 42. Before reaching the delivery table 37, the board 17 passes between the compression 110 rollers 44 and 45, geared together and driven by the sprocket chain 46 engaging a sprocket 47 on the shaft 21 of the feed roll 19, whereby these compression rolls operate in unison with the feed roll. In starting, 115 the end of the paper 38 is carried down in front of the rolls 44 and 45 between which it is pushed by the approaching end of the board 17 on its travel through the machine. The roll 44 presses the paper 38 against the 120 upper surface of the board 17 to which it is caused to adhere by the paste covering one side of the holes 48 to form recesses in the

wall boards, resulting in the product illustrated in Fig. 9.

It is the particular function of the paper 38 which has been previously water proofed to make the back side of the board impervious to moisture to prevent sweating and to prevent the emergence of the key formed by the applied coat of plaster protruding through the hole 48 in the board 17. Where 10 it is desired to produce a plaster board having the advantages as set forth, plus the additional advantages of being fire-proof, the paper 38 can be treated with suitable fire-proofing solution, or it may be composed of 15 asbestos or another non-inflammable material, by which means the plaster board having a non-inflammable back and a coating of non-inflammable plaster on the opposite side forms a fire proof wall or partition. 20 So far as I am aware I am the first to produce such a wall in this manner.

To improve the keying qualities of the hole 48, they are countersunk by the tapered shoulder 18 on the male punches as previously described, producing a hole smaller in diameter on the plaster side of the board than on the back which is covered by the sheet 38. This results in forming a key integral with the plaster Y and taking the 25 form Y¹ as illustrated in Fig. 11, the form of the hole forming a clench or rivet-like bond between the plaster Y and the wall board 17, in addition to the natural adhesion between the plaster and the surface of 30 the wall board between the openings, the dove-tail shape of the key Y¹ insuring a mechanical bond in addition to its adhesion to the surrounding wall board. The countersinking of the holes has the further advantage that it can be made to fracture or 35 shatter the adjacent plaster core to improve the keying qualities of the bond; particularly where small, straight, or inclined holes are punched. The punches may be of forms 40 to punch holes of any desired shape and the holes may be variously spaced.

In Fig. 12 is illustrated a hollow punch 50 adapted to be forced into the wall board through the paper X' and the core X leaving the paper X² intact. The rise of the punch lifts the punching 51 out of the wall board. This punching 51 is ejected from the punch by the stripper 52 actuated by the expansion of the spring 53, the stripper 55 being held in assembly by the slots 54 engaging the screws 55 in the punch 50; this 55 form of punch forms a recess such as 56, see Fig. 13. If it is desired in addition to puncture the paper backing X² as at 57, the punch 58 can be combined with the punch 50 to coöperate with the die 59 to punch the hole 57, which permits the plaster coating to pass through the wall board and clench. 60

This hollow type of punch is desirable 65 when the wall board is to be treated in the

moist or semi-stable state as it comes from the machine within which it is fabricated.

While I have laid particular stress upon the advantages of punching wall board after it has set or dried, in which stable state 70 it is more easily processed and produces a superior article for the purpose; I do not wish to be understood as limiting this invention thereby, as it can be punched during its various stages of production or curing 75 with various results.

Having thus described this invention, what I claim and desire to secure by Letters Patent is:

1. A process of manufacturing wall 80 board comprising flowing a core of plastic material between reinforcing sheets of paper, allowing the same to stand until dry, and then punching holes through the completed board.

2. A process of manufacturing wall board comprising flowing a core of plastic material between reinforcing sheets of paper, pressing the same into flat sheets, allowing said sheets to stand until dry, and then 90 punching holes through the dry sheets.

3. A process of manufacturing wall board comprising flowing a core of plastic material between reinforcing sheets of paper, allowing the same to stand until dry, and then 95 punching tapered holes through the dry board.

4. A process of manufacturing wall board comprising flowing a core of plastic material between reinforcing sheets of paper, allowing the same to stand until dry, then 100 punching holes through the completed board, and enlarging said holes by compression.

5. A process of manufacturing wall board 105 comprising flowing a core of plastic material between reinforcing sheets of paper, allowing the same to stand until dry, and then punching holes through the dry board in such manner as to shatter the substance of 110 the board adjacent to the hole.

6. The process of treating dry wall board consisting in punching holes therethrough and covering one side of said holes to form a recess in said wall board. 115

7. An article of manufacture consisting of a sheet of wall board composed of a core of dry plaster between reinforcing sheets having holes punched therethrough while in the dry state, and a sheet of fire proof material applied to one side of said board after 120 said punching operation.

In testimony whereof I have hereunto set my hand at San Francisco, California, this 7th day of August, 1917.

JOHN F. MAKOWSKI.

In the presence of—

BALDWIN VALE,
LINCOLN V. JOHNSON.
